US0D1062159S

(12) United States Design Patent (10) Patent No.: US D1,062,159 S
(45) Date of Patent: * Feb. 18, 2025

(54) SHOE

(71) Applicant: adidas AG, Herzogenaurach (DE)

(72) Inventor: Randall Yarborough, Los Angeles, CA
(US)

(73) Assignee: adidas AG, Herzogenaurach (DE)

() Term: 15 Years

(21) Appl. No.: 29/831,453

(22) Filed: Mar. 21, 2022

Related U.S. Application Data

(63) Continuation of application No. 29/728,283, filed on Mar. 17, 2020, now Pat. No. Des. 1,009,413.

(30) Foreign Application Priority Data

Sep. 17, 2019 (EM) 006879797

(51) LOC (15) Cl. 02-04

CLAIM

The ornamental design for a shoe as shown and described.

DESCRIPTION

FIG. 1 is a perspective view of a shoe, showing my new design.

FIG. 2 is a front view of the shoe of FIG. 1.

FIG. 3 is a back view of the shoe of FIG. 1.

FIG. 4 is a side view of the shoe of FIG. 1.

FIG. 5 is another side view of the shoe of FIG. 1, from the opposite side as FIG. 4.

FIG. 6 is a top view of the shoe of FIG. 1; and,

FIG. 7 is a bottom view of the shoe of FIG. 1.

The broken lines and the reduced opacity areas within the broken lines show portions of the shoe that form no part of the claimed design.

1 Claim, 7 Drawing Sheets
